UNITED STATES PATENT OFFICE.

AUBREY S. HELM, OF WAURICA, OKLAHOMA.

VALVED FLUE FOR COTTON GINS.

Application filed March 5, 1928. Serial No. 259,201.

This invention relates to lint flues for cotton gins and more particularly to a controlling means therefor, and has for its primary object to prevent the cotton from backing 5 up the lint flue to the gin stand in cases where the driving belt for the gin stand breaks or slips.

A further object is to provide a means as aforesaid, which is particularly applicable 10 where several gin stands are used in a battery to feed a common condenser and press flue.

A further object is to provide a lint flue as hereafter described, including an automatically operable controlling valve therefor.

15 A further object is to provide a valve as aforesaid, which may be economically manufactured and readily installed in the flues of cotton gins now in common use, and known as brush gins.

20 Other objects and advantages of the invention will be apparent during the course of the following description.

In the accompanying drawings, in which like numerals are employed to designate like 25 parts throughout the same.

Figure 1 is a top plan view of a flue leading to a condenser shown at one end thereof, and showing a battery of gin stands, each having a flue emptying into the condenser flue,

30 Figure 2 is an enlarged section of the condenser flue and one of the gin stand flues connected thereto, taken on the line 2-2 of Figure 1, looking in the direction of the arrow,

Figure 3 is an enlarged, fragmentary, 35 longitudinal section of a condenser flue showing the mouth of a gin stand flue in dotted lines and my valve therefor in elevation, and,

Figure 4 is an enlarged detail, perspective view of the valve and fasteners.

40 In the drawings, wherein for the purpose of illustration is shown a preferred embodiment of my invention, the numeral 5 designates, as a whole, a condenser and press showing the relative position thereof, to a condenser flue 6, which feeds the same, the end 7 of the flue 6, opposite to the condenser 5, being closed.

Connected to the condenser flue 6, in spaced apart relation, is a plurality of gin stand 50 flues 8, each leading from a gin stand, indicated as a whole at 9, and each of the gin stand flues having an open end 10, emptying into the condenser flue 6, all of the foregoing description being of usual and well known 55 construction.

In the present operation of gins as above

described, it often happens that one of the gin stands becomes temporarily disabled, by reason of a broken or slipped belt, or the like, and during such term of disability, the flue from that particular gin stand no longer functions as a means for conveying cotton to the condenser flue, which is common to all the gin stands. At such times, the cotton from the remaining gin stand flues enters the 60 mouth 10 of the inactive flue, and backs into the disabled gin stand, where it winds around the brush and saws, causing a great deal of damage to the stand and resulting in a great 65 loss of time.

To eliminate this loss of time and damage to machinery, I provide the open end 10, of each gin stand flue 8, with a valve 11, which may be made of metal, wood or other suitable material and may be installed in the flues 70 of any gin of the well known brush gin type.

The valve 11 may be hinged or pivoted to the interior surface of the flue 6 by any suitable means, such as strap fasteners 12, which may be secured to the wall of the flue 6 by 75 pivots 13, or the like, and which may have rolled edges 14, fitting into recesses 15, formed in the rolled edge 16 of the valve 11, the rolled edges 14 and 16, being in longitudinal alinement and receiving loosely therethrough a pivot pin 17, the details of the above described assembly being clearly 80 shown in Figure 4.

The valve 11 is arcuate in shape, to conform 85 in contour to the interior of the flue 6, and is longer and wider than the opening 10, being so disposed within the flue 6, relative to the opening 10, that the opening is completely covered with the valve in closed position.

In operation, a current of air which is set 90 up in each gin stand 9 forces open the valve 11 for the corresponding gin stand flue 8 and passes the cotton through such flue 8 into the flue 6. If, for any reason, the current of air is stopped in a flue 8 and the cotton stops 95 coming through such flue, the corresponding valve 11 immediately swings downwardly by gravity to close the opening 10, thereby preventing any of the cotton in the flue 6, passing the opening 10 from one of the other gin stands, from entering the opening 10 and 100 backing up to the gin stand.

It is to be understood that the form of my 105 invention herewith shown and described is to be taken as a preferred example of the same, and that various changes in the shape, size, and arrangement of parts may be re-

sorted to without departing from the spirit of the invention or the scope of the appended claims.

What I claim is:—

- 5 1. In combination with a condenser flue and a gin stand flue opening thereinto, a valve for controlling the opening and adapted to be forced open by air to permit the passage of the contents of the gin stand flue into
- 10 10 the condenser flue, said valve being normally closed by gravity to prevent the passage of the contents of the condenser flue backing into the gin stand flue.
- 15 2. In combination with a condenser flue having an opening in the wall thereof, and a gin stand flue emptying through said opening into said condenser flue, a valve of greater area than that of the opening, hingedly mounted on the interior of the condenser
- 20 20 flue, adjacent to and above the opening, said valve being normally closed by gravity to prevent the contents of the condenser flue from passing into the gin stand flue and adapted to be swung away from said opening by air passing through said gin stand
- 25 25 flue to permit the passage of the contents of the gin stand flue into the condenser flue.

3. In combination with a gin stand flue and a condenser flue having an opening in the wall thereof connecting the interiors of said flues, a valve conforming in contour to the interior wall in which the opening is formed, and mounted relative to the opening to normally operate by gravity to close the passage from the condenser flue to the gin stand flue, and to open into the condenser flue when air is directed through the gin stand flue against the valve to permit the contents of the gin stand flue to enter the condenser flue.

4. In combination with a plurality of gin stand flues and a common condenser flue having an opening in the wall thereof for communication with each gin stand flue, a gravity operated valve for each communicating opening to normally close the latter, each of said valves being hinged within the condenser flue longitudinally thereof to permit the valve to swing in an arc transversely of the condenser flue.

In testimony whereof I affix my signature hereto.

AUBREY S. HELM.
